ATARACTIC COMPOSITION COMPRISING 10-(1-METHYL-3-PIPERIDYL METHYL)-PHENOTHIAZINE AND 10-(3-DIMETHYL-AMINO-PROPYL)-2-CHLOROPHENOTHIAZINE

Henry Angus Bowes, Baie d'Urfée, Quebec, Canada, assignor to Warner-Lambert Pharmaceutical Company, Morris Plains, N. J., a corporation of Delaware

No Drawing. Application September 21, 1956
Serial No. 611,350

6 Claims. (Cl. 167—65)

This invention relates to new and improved ataractic compositions.

Ataractic drugs are so called by reason of their ability to produce ataraxy which, in medical terminology, means "freedom from confusion and anxiety." These drugs are also known as tranquilizing drugs. The mounting interest in the use of ataractic drugs in conjunction with psychotherapy for the treatment of various types of mental illness has drawn attention to the undesirable as well as to the desirable effects that such drugs have produced in patients receiving them. Only too frequently does optimism of early trials give way to cautious restraint in later trials by reason of undesirable side reactions produced by such drugs.

Among the drugs which have been found effective in the management of many types of mental illness are the following two drugs identified by name and structural formula:

Mepazine or 10-(1-methyl-3-piperidylmethyl)-phenothiazine

Chlorpromazine or 10-(3-dimethylaminopropyl)-2-chlorophenothiazine

Each of these two drugs has received extensive clinical evaluation and there is ample evidence that they both afford symptomatic relief of psychomotor excitation, aggression, destruction, restlessness and tension in acute and chronic psychoses. However, it has been observed that in certain patients Mepazine is apt to produce such undesirable side effects as dry mouth, constipation and difficulty in accommodation, and that these effects are due to the parasympatholytic character of the drug. Similarly Chlorpromazine is known to produce a number of side effects such as agranulocytosis, jaundice, Parkinsonism, heaviness and drowsiness, and it is recognized that some of these complications are due to the sympatholytic character of the drug.

It is an object of this invention to provide an ataractic composition which affords the beneficial effects of Mepazine and Chlorpromazine, in mentally disturbed patients, but which does not produce the undesirable side reactions characteristic of Mepazine and Chlorpromazine. Further objects of this invention will be apparent from other disclosures set forth hereinbelow.

2

The composition of this invention comprises a mixture of the two drugs Mepazine and Chlorpromazine incorporated into suitable pharmaceutical carriers for the preparation of dosage unit forms comprising tablets, capsules, elixirs, parenterals, suppositories and the like, examples whereof are described hereinbelow. The said two drugs may be used either in the form of the free base or as nontoxic acid-addition salts thereof such as the hydrochlorides, sulfates, acetates, lactates, succinates, malates and the like.

In accordance with this invention there has been found, surprisingly, that Mepazine and Chlorpromazine act synergistically in the composition of this invention. Thus the tranquilizing effect of the said composition was found to be consistently greater than might be expected from a mere summation of the tranquilizing effects due to the two component drugs individually in the same dosage for each as was used in the said composition, and also consistently greater than the tranquilizing effect obtained when either of the two drugs was used alone in a dosage equal to the sum of the dosages of the said two drugs in the said composition. A further advantage of the composition of the invention is that the two drugs thereof are mutually antagonistic to each other's complications. Further, the coadministration of the two drugs obviated the instances of the separate use of Mepazine in those patients, usually those of asthenic build, who are helped more by Chlorpromazine than by Mepazine, and conversely of the separate use of Chlorpromazine in those patients, usually of pyknic build, who are helped more by Mepazine than by Chlorpromazine. The composition of this invention may contain Mepazine and Chlorpromazine in various ratios. A predominant proportion of Chlorpromazine is indicated for use in the asthenic who is prone to feel anxiety at an adrenergic level. Mepazine would be used in a much higher proportion than Chlorpromazine in the pyknic whose anxiety is frequently manifested at a cholinergic level. The proportion of the two drugs, in the composition of this invention, may be adjusted to suit the individual patient after an appraisal of where this patient lies between these extremes. In most cases compositions containing equal parts of Mepazine and Chlorpromazine have been found to be broadly effective.

The administered dosage of the composition of the invention in the form of tablets, capsules, elixir and suppositories, varies broadly and may be adjusted to the requirements of the individual patients. In general, patients are started on a total dosage of 100 to 300 mg. of the active ingredients administered three times daily whereafter the dosage is adjusted up or down until the desired degree of tranquilization is obtained. Usually the adjusted dosages for various patients fall within the range 75 to 900 mg. daily. By the parenteral route the dosage range is usually 50 to 200 mg. daily.

Although the exact mechanism of action of the ataractic composition of this invention is not known, it is believed that the said composition works centrally by depressing the outflow of both the sympathetic and parasympathetic nervous systems, thus reducing the physical concomitance of anxiety. The patient is freed from his sweating, tremors, palpitations and gastrointestinal upset and thus is able to take a more objective view of his emotional problems with which he may now cope with the aid of psychotherapy. In addition his drive is sufficiently reduced so that the fear of losing self-control is markedly diminished.

The invention is illustrated by the following examples:

EXAMPLE I
Tablet composition

Ingredients:	Quantity for 1000 tablets
(1) Mepazine hydrochloride	12.5
(2) Chlorpromazine hydrochloride	12.5
(3) Methylcellulose, 400 cps., NF	5.5
(4) Starch, U. S. P.	11.0
(5) Lactose, U. S. P., free-flowing	55.4
(6) Water, potable, q. s. or about	30.0
(7) Magnesium stearate	2.2
(8) Starch, dried, q. s. or about	5.9
To make	105.0

Pass the powders separately through a No. 40 screen. Mix 3 and 4, then add 1, 2 and mix. Then add 5 serially, mixing after each addition. Granulate with 6 and pass the moist mass through a No. 16 screen. Dry at room temperature (or at 30° C.) overnight and pass the dried granules through a No. 20 screen. Add 7 and 8 through a No. 60 screen and blend well. Compress 105.0 mg. per tablet on $\frac{1}{4}$ -inch, standard concave, scored punches at 2-3 kg. hardness and 0.135-0.145 inch thickness.

EXAMPLE II

Tablet composition

Ingredients:	Quantity for 1000 tablets, grams
(1) Chlorpromazine hydrochloride	20.00
(2) Mepazine hydrochloride	80.00
(3) Starch, U. S. P.	32.50
(4) Methylcellulose, U. S. P., 400 cps	32.50
(5) Lactose, U. S. P., free-flowing	141.75
(6) Magnesium stearate, U. S. P.	3.25
To make	310.00

Pass the powders through a No. 30 screen and blend thoroughly in the twin-cone blender. Granulate by dry compression and break up slugs through a No. 16 screen. Mix to insure even granule distribution. Compress 310 mg. per tablet on a $\frac{3}{8}$ -inch, standard concave, scored punches at 3-5 kg. hardness and 0.175-0.185 inch thickness.

EXAMPLE III

Tablet composition

Ingredients:	Quantity for 1000 tablets, grams
(1) Mepazine hydrochloride	25.00
(2) Chlorpromazine hydrochloride	75.00
(3) Starch, U. S. P.	32.50
(4) Methylcellulose, U. S. P., 400 cps	32.50
(5) Lactose, U. S. P., free-flowing	141.75
(6) Magnesium stearate, U. S. P.	3.25
To make	310.00

Pass the powders through a No. 30 screen and blend thoroughly in the twin-cone blender. Granulate by dry compression and break up slugs through a No. 16 screen. Mix to insure even granule distribution. Compress 310 mg. per tablet on a $\frac{3}{8}$ -inch, standard concave, scored punches at 3-5 kg. hardness and 0.175-0.185 inch thickness.

EXAMPLE IV

Tablet composition

Ingredients:	Quantity for 1000 tablets
(1) Mepazine hydrochloride	100.0
(2) Chlorpromazine hydrochloride	100.0
(3) Starch, U. S. P.	44.0
(4) Methylcellulose, U. S. P., 400 cps	44.0
(5) Lactose, U. S. P., free-flowing	68.1
(6) Water, potable, q. s. or about	100.0
(7) Magnesium stearate, U. S. P.	4.0
(8) Starch, U. S. P., dried, q. s. or about	4.9
To make	365.0

Mix 1, 2, 3, 4 and add 5 by geometric dilution and pass the powders through a No. 30 screen. Granulate with 6 mixing until proper granule size is obtained. Dry 20 overnight at room temperature (or at 30° C.) and pass the dried granules through a No. 14 screen on the Stokes oscillating granulator. Add 7 and 8 through a No. 40 screen and blend thoroughly. Compress 365 mg. on $1\frac{1}{2}$ -inch, standard concave punches at 4-6 kg. hardness 25 and 0.20-0.21 inch thickness.

EXAMPLE V

Capsule composition

Ingredients:	Quantity for 1000 capsules, grams
(1) Mepazine hydrochloride	12.5
(2) Chlorpromazine hydrochloride	12.5
(3) Lactose, U. S. P., free-flowing	415.8
(4) Magnesium stearate	9.2
To make	450.0

Pass the powders separately through a No. 40 screen. Then mix 1, 2 with 3 in divided portions, mixing after each addition. Then add 4 and blend thoroughly. Fill 450 mg. into No. 1, two-piece, hard gelatin capsules.

EXAMPLE VI

Parenteral composition

Ingredients:	Quantity for 1000 ml.
(1) Mepazine lactate	162.0
(2) Chlorpromazine lactate	162.0
(3) Water for injection, U. S. P., q. s. ml.	1000.0

Boil 800 ml. of 3 for 30 minutes, cool at room temperature in a stream of nitrogen. Add 1, 2 and enough 55 boiled 3 to a total volume of 1000 ml. Shake well to dissolve, filter through medium porosity sintered glass filter with 3 Whatman filter paper on top into an amber bottle filled with nitrogen. Fill 2.2 ml. into amber 2 ml. constructed neck ampuls previously filled with nitrogen, and 60 seal.

EXAMPLE VII

Parenteral composition

Ingredients:	Quantity for 10 liters
(1) Mepazine acetate	164.0
(2) Chlorpromazine acetate	164.0
(3) Sodium acetate, U. S. P., reagent	100.0
(4) Acetic acid, U. S. P., q. s., pH 5.5-5.9, about	75.0
(5) Water for injection, U. S. P., q. s. liters	10.0

Boil 8 liters of 5 for 30 minutes, cool to room temperature in a stream of nitrogen. Add 1, 2 and 3 dissolved in about 200 ml. of boiled 5. Adjust pH to 5.5-75 5.9 by addition of 4 and add enough boiled 5 to a total

of 10 liters. Shake well to dissolve, filter through a sterile Seitz filter previously rinsed with sterile water. Subsequently filter through a sterile sintered glass funnel of fine porosity, into a sterile amber bottle filled with nitrogen. Aseptically fill 2.2 ml. into sterile amber 2 ml. ampuls previously filled with nitrogen, and seal.

EXAMPLE VIII

Elixir composition

Ingredients:	Quantity for 1000 ml.
(1) Mepazine hydrochloride	2.00
(2) Chlorpromazine hydrochloride	2.00
(3) Alcohol, U. S. P., 10 percent	100.00
(4) Kristo Kleer VC	750.00
(5) Menthol, U. S. P.	0.10
(6) Imitation cachaoumint flavor	0.17
(7) Benzoic acid, U. S. P., 0.03 percent	0.30
(8) Sodium benzoate, 0.02 percent	0.28
(9) Water, potable, q. s., about	1000.00

Add 1, 2 to 3 with stirring followed by 5, 7, 6 and 80 ml. of 9. When solution is complete add 8, 4 and q. s. with 9. Mix well, and filter through a coarse sintered glass funnel.

EXAMPLE IX

Suppositories composition

Ingredients:	Quantity for 1000 g., g.
(1) Mepazine hydrochloride	50.0
(2) Chlorpromazine hydrochloride	50.0
(3) Cocoa butter substitute, q. s.	1000.0

Melt 3 on a steam bath. Add 1, 2 and stir until uniform. At about 40° pour into chilled suppository molds. Allow to solidify at room temperature for about 15 minutes then keep at 5° C. for about 30 minutes.

EXAMPLE X
Suppositories composition

Ingredients:	Quantity for 1000 g., g.
(1) Mepazine hydrochloride	30.0
(2) Chlorpromazine hydrochloride	70.0
(3) Cocoa butter substitute, q. s.	1000.0

The suppositories are prepared in the manner described in Example IX.

EXAMPLE XI

Suppositories composition

Ingredients:	Quantity for 1000 g., g.
(1) Mepazine hydrochloride	80.0
(2) Chlorpromazine hydrochloride	20.0
(3) Cocoa butter substitute, q. s.	1000.0

Suppositories are prepared in the manner described in Example IX.

10 Since certain changes may be made in the compositions above described without departing from the scope of this invention, it is intended that all matter contained in the above description shall be interpreted as illustrative, and not in a limiting sense.

15 What is claimed is:

1. An ataractic composition having as an active ingredient a mixture of substance A and substance B, said substance A being a member selected from the group consisting of 10-(1-methyl-3-piperidylmethyl)phenothiazine and the nontoxic salts thereof, and said substance B being a member selected from the group consisting of 10-(3-dimethylaminopropyl)-2-chlorophenothiazine and the non-toxic salts thereof, said composition also comprising a pharmaceutical carrier.

20 2. The composition of claim 1 where said composition is in the form of tablets.

3. The composition of claim 1 wherein said composition is in the form of capsules.

4. The composition of claim 1 wherein said composition is in the form of an elixir.

5. The composition of claim 1 wherein said composition is in the form of a parenteral preparation.

6. The composition of claim 1 wherein said composition is in the form of suppositories.
